[57] **CLAIM**

The ornamental design for a combined trunk for a motorcycle and a base plate therefor, as shown and described.

DESCRIPTION

FIG. 1 is a front perspective view of a combined trunk for a motorcycle and base plate thereof showing my new design;

FIG. 2 is a front view;

FIG. 3 is a rear view;

FIG. 4 is a top view;

FIG. 5 is a bottom view;

FIG. 6 is a left side view;

FIG. 7 is a right side view;

FIG. 8 is a front perspective view with the lid in open condition;

FIG. 9 is a bottom perspective view with the base plate detached; and,

FIG. 10 is a front perspective view with the motorcycle shown in broken lines for illustrative purposes only and forming no part of the instant invention.

FIG. 1

FIG. 2

FIG. 3

FIG. 4

FIG. 5

FIG. 6

FIG. 7

FIG. 8

FIG. 9

FIG. 10
